[57] CLAIM

The ornamental design for an automotive floor mat, as shown and described.

DESCRIPTION

FIG. 1 is an exploded perspective view of an automotive floor mat with hook and loop fastener detached showing our new design;

FIG. 2 is a top view thereof;

FIG. 3 is a bottom view of the floor mat of FIG. 2, with the hook and loop fastener attached;

FIG. 4 is a right side view of the floor mat of FIG. 2;

FIG. 5 is a left side view thereof with hook and loop fastener detached therefrom;

FIG. 6 is a front view of the floor mat of FIG. 2; and,

FIG. 7 is a rear view of the floor mat of FIG. 2.
